CORE BARREL

Clarence E. Burt, Los Angeles, Calif., assignor to
 Baker Oil Tools, Inc., Huntington Park, Calif.,
 a corporation of California

Application November 23, 1935, Serial No. 51,281

4 Claims. (Cl. 255—72)

This invention relates to oil well drilling tools and particularly pertains to core barrels. Rotary core barrels for taking samples or cores of formation to be penetrated by the well bore 5 are in general use. These core barrels usually comprise an outer drill barrel fitted with a bit at its lower end, which barrel is revolved by the drilling stem to cut or form a core. Arranged within the drill barrel is a core recovery tube 10 which passes over the core as the core barrel advances through the formation, the core remaining in this core recovery tube when the drill barrel is removed from the bore. The drilling fluid is usually pumped downwardly through the drilling 15 stem, thence between the drill barrel and the core tube to discharge at the bit. Prior core barrels have not been entirely successful due to the fact that it is extremely seldom that a true core of the entire formation penetrated is recovered. In 20 fact, the percentage of recovery has been small and has depended upon the character of formation being cored and the efficiency of the particular core barrel employed as well as the expertise of the driller.

It is the principal object of my invention to provide an improved rotary core barrel capable of effecting a maximum recovery of a core from the formation penetrated by the core barrel.

I accomplish this object by providing a core 30 barrel having a drill barrel within which a core recovery tube is suspended. I utilize the drilling fluid pumped downwardly to the bit to create a suction tending to evacuate the core recovery tube from its upper end, and thereby creating a reduced pressure area within the core tube so that the differential pressure between the interior pressure in the core tube and the external pressure in the well bore will aid in projecting the core upwardly into the core tube and thus insure 35 a maximum recovery.

One form which the invention may assume is exemplified in the following description and illustrated by way of example in the accompanying drawing, in which:

Fig. 1 is a central vertical section of a core barrel constructed in accordance with my present invention.

Fig. 2 is a view in section and perspective of the water-jet pump portion of my core barrel.

Fig. 3 is a transverse sectional view taken on line III—III of Fig. 1.

Referring more particularly to the accompanying drawing, 10 indicates a rotary core barrel which comprises a drill barrel 11 fitted at its upper end with a sub 12 by means of which it may be

connected with the lower end of a drilling stem. The lower end of the drill barrel 11 is fitted with the usual bit 14 for penetrating into the formation when the drill barrel is revolved by the drilling stem to form a core 15.

Suspended concentrically within the drill barrel 11 is a core recovery tube 16, the lower end of which is fitted with the usual core trimmer shoe 17 which also is provided with a suitable type of core catcher 18. It will be noticed that the external diameter of the core recovery tube 16 is somewhat less than the internal diameter of the drill barrel 11 so that an annular space occurs therebetween through which the drilling fluid may travel from the drill stem to the bit 14.

The upper end of the core recovery tube 16 is fitted with a two-part core tube head 19, consisting of a lower portion 20 and an upper portion 21 which are threadedly connected as illustrated. The upper end of the core tube head 19 is connected to the sub 12 by a suitable swivel connection 22, which enables the drill barrel 11 to revolve relative to the core tube 16 and its head 19, but which prevents relative axial movement therebetween.

It is intended that when the core barrel here disclosed is in operation, that the drill barrel 11 revolve so that it will advance into the formation, while the core tube 16 will advance axially with the drill barrel so that it will pass over the core, but due to its swivel connection with the drill barrel, it will not revolve.

Fixed by welding or any other suitable connection within the tubular lower portion 20 of the core tube head 19 is a strainer body 23, which is hollow and cylindrical. At its lower end the interior of this strainer body 23 is formed with a restricted passageway 24 having a valve seat 25 at the point where it joins the interior of the body 23. A ball valve 26 is adapted to seat on this seat 25 to prevent the passage of fluid downwardly into the upper end of the core tube. The lower end of the strainer body 23 below the restricted passageway 24 terminates in a strainer 27.

It will be noticed that the strainer head 23 is provided with vertical channels 28 extending from its upper to its lower end, so that fluid from within the core tube 16 may pass upwardly through the strainer 27, and thence upwardly past the strainer head 23 through the channels 28, which channels will occur between the interior periphery of the lower portion 20 of the core tube head 19 and the strainer head 23. Likewise, fluid from the core tube may pass upwardly through 55

the restricted passageway 24 by unseating the valve 26 into the interior of the strainer head 23. Radial ports 29 are formed through the sides of the strainer head 23 between the channels 28, which ports register with similar ports 30 formed through the wall of the lower portion 20 of the core tube head 19. Therefore, when fluid passes upwardly through the restricted passageway 24 by unseating the valve 26, it will then pass into the interior of the strainer head 23 and may discharge through the ports 29 and 30 into the annular space between the core tube and the drill barrel.

Arranged concentrically within the core tube head 19 above the strainer head 23 is a nozzle 31, the lower end of which fits in a counterbore 32 formed within the upper end of the strainer head 23. The upper end of the nozzle fits within the bore 34 of the upper end of the lower portion 20 of the core tube head 19. A gland 35 is threaded into the upper extremity of the lower portion 20 of the head 19 to secure the nozzle 31 in position.

It will be noticed that the diameter of the bore of the nozzle at its lower extremity agrees with the internal diameter of the strainer head 23, while the internal diameter of the nozzle at its upper extremity agrees with the internal diameter of the gland 35.

It will therefore be seen that due to the fact that the upper portion 21 of the core tube head 19 is hollow, cylindrical and open-ended, that drilling fluid pumped downwardly through the drilling stem will pass into the upper end of the core tube head 19 and then must pass downwardly through the nozzle 31 and thence outwardly through the ports 29 and 30 into the annular space between the core tube and the drill barrel. It may pass downwardly through this annular space and discharge at the bit in the usual manner.

I utilize the drilling fluid to create a suction in the upper end of the core tube to partially evacuate the latter and thereby create a differential pressure between the interior of the core tube and the exterior thereof. This differential in pressure aids in projecting the core upwardly into the core tube so that a maximum recovery of the core will be effected.

It will be noticed that the nozzle 31 is in the form of a Venturi tube so that when the drilling fluid passes downwardly therethrough, its velocity will be increased. Small orifices 36 are formed through the wall of the nozzle 31 just below its restricted throat so that the fluid passing downwardly through the nozzle will create a suction through these orifices 36. Due to the fact that there is an annular space within the core tube head 19 surrounding the nozzle and communicating with the orifices 36, which annular space 55 communicates with the interior of the core tube at its upper end through the channels 28, the suction created through the orifices 36 will draw the fluid in the core tube 16 upwardly and discharge it through the orifices 36 into the drilling fluid stream. In other words, there will be an evacuating action tending to evacuate the core tube and reduce the pressure therein to a pressure under that in the surrounding well bore. It is obvious that the differential in pressure will tend to force the core upwardly into the core tube.

What I have done in effect is to provide a water-jet pump with its suction communicating with the interior of the core tube at its upper end, and which utilizes the drilling fluid as the medium for evacuating the core tube.

In operation of the device, it is constructed and assembled substantially as shown in the drawing and the drill barrel sub 12 is connected to the lower end of a drilling string. The device is then lowered into the well bore. It is sometimes preferable not to position the ball valve 26 until the core barrel is at the bottom of the bore and ready for operation. This is so that drilling fluid may be pumped downwardly through the drilling stem and thence downwardly through the core tube 10 to wash the same out before commencing coring operations.

After the washing action has been complete, the ball valve 26 is dropped downwardly through the drilling string where it will find its seat on the seat 25. The drilling string is then revolved and sufficient weight is employed so that the drill barrel 11 will advance through the formation, cutting an annulus therein and forming the core 15, which will be in alignment with the core recovery tube 16, so that it will project thereinto.

While the drilling is going on, drilling fluid under considerable pressure is continuously pumped downwardly through the drilling string to lubricate the bit 14. This drilling fluid will pass downwardly through the upper portion 21 of the core tube head 19 and thence pass through the nozzle 31 and discharge through the ports 29 and 30 to the annular space between the core tube and the drill barrel. It will, of course, travel downwardly through this annular space to discharge at the bit. During the passage of the drilling fluid through the nozzle 31, its velocity will be accelerated due to the Venturi shape of the nozzle 31 and will create a suction through the orifices 36, tending to create a partial vacuum in the space surrounding the nozzle 31 which is in communication only with the upper end of the core tube. This will, of course, tend to evacuate the upper end of the core tube and will 40 reduce the pressure therein to a pressure lower than the pressure in the surrounding well bore. The differential in pressure will tend to force the core upwardly into the core tube and insure a maximum recovery thereof.

It is obvious from the foregoing that I have provided a rotary core barrel which is comparatively simple in construction and operation and which will be effective in obtaining a maximum core recovery of the formation penetrated.

While I have shown the preferred form of my invention, it is to be understood that various changes may be made in its construction by those skilled in the art without departing from the spirit of the invention as defined in the appended claims.

Having thus described my invention, what I claim and desire to secure by Letters Patent is:

1. A rotary core barrel including a drill barrel adapted to be connected to the lower end of a drill stem in a manner where circulating fluid pumped downwardly through the drill stem will enter the upper end of the drill barrel, a core tube mounted within the drill barrel, a central nozzle member arranged within the drill barrel with its upper end in the line of flow of fluid from the drill stem and its lower end in communication with the space between the drill barrel and the core tube, said nozzle having orifices therein in communication with the interior of the core tube whereby the flow of fluid through said nozzle will create a suction through said orifices tending to evacuate the core tube.

2. A rotary core barrel including a drill barrel adapted to be connected to the lower end

of a drill stem, a core recovery tube suspended in said drill barrel, there being an annular space between the exterior of the core tube and the interior of the drill barrel, a rotary connection 5 between the upper end of the core tube and the drill barrel enabling fluid from the drill stem to be pumped therethrough into the annular space between the drill barrel and the core tube but not into the upper end of the core tube, 10 a nozzle incorporated in said connection through which the fluid must pass, said nozzle having orifices in communication with the interior of the core tube whereby the flow of fluid through the nozzle will create a suction through said orifices 15 tending to evacuate said core tube.

3. A rotary core barrel including a drill barrel adapted to be connected to the lower end of a drill stem, a core recovery tube mounted therein, a swivel connection suspending said 20 core tube within the drill barrel, said swivel connection including a nozzle in the form of a Venturi tube through which fluid pumped downwardly through the drill stem must pass, the lower end of said nozzle being in communication 25 with a space between the exterior of the core

tube and the interior of the drill barrel, said nozzle having orifices in communication with the interior of the core tube whereby passage of fluid through the nozzle will create a suction through said orifices tending to evacuate 5 said core tube.

4. A device for use in oil well bores including an outer tubular member adapted to be connected to the lower end of a drill stem, an inner tubular member suspended within said outer tubular member in a manner permitting the outer tubular member to rotate relative thereto, the upper end of the inner tubular member being closed to the flow of fluid pumped downwardly through the drill stem into the upper end of the outer tubular member, a nozzle in the form of a Venturi tube within the upper end of the outer tubular member through which the flow of fluid from the drill stem must pass, said nozzle having orifices formed therein in communication with the inner tubular member whereby a flow of fluid through the nozzle will create a suction through said orifices tending to evacuate 10 15 20 25 said inner tubular member.
